DESIGN FOR A GARMENT SUPPORTER

Walter M. O'Neal, Grass Valley, Calif.

Application February 20, 1943, Serial No. 109,587

Term of patent 14 years

(Cl. D3—10)

To all whom it may concern:

Be it known that I, Walter M. O'Neal, a citizen of the United States, residing at Grass Valley, in the county of Nevada, and State of California, have invented a new, original, and ornamental Design for a Garment Supporter, of which the following is a specification, reference being had to the accompanying drawing, forming part thereof.

I claim:

The ornamental design for a garment supporter, as shown.

WALTER M. O'NEAL.
